EDGE GRINDING MACHINE FOR STRIP MATERIAL

Paul E. Carrick, Birmingham, Mich.

Application May 19, 1943, Serial No. 487,609

6 Claims. (Cl. 51—78)

The present invention relates to an automatic grinding machine for grinding a radius on strip material.

It is the general object of the present invention to provide a machine of rugged and simple construction for automatically feeding strip material past one or more grinding wheels and oscillating the work relative to the wheel during the grinding operation in order to form a radius on the material.

Another object of the invention is to provide a work supporting and feeding means of the type mentioned which is adapted for use in connection with conventional grinding machines of the type in which the grinding wheel spindle is carried at the end of an overhanging arm.

Other objects of the invention will become apparent from the following specification, the drawings relating thereto, and from the claims herein-after set forth.

In the drawings, in which like numerals are used to designate like parts in the several views throughout:

Figure 1 is a side elevation of the machine;

Figure 2 is an end elevation of the machine, including a fragmentary illustration of the independent support for the grinding wheels;

Figure 3 is a fragmentary vertical section taken on the line 3—3 of Figure 2, with parts broken away to show the interior construction;

Figure 4 is a fragmentary transverse section taken on the line 4—4 of Figure 3;

Figure 5 is a fragmentary plan view of the machine with the grinding wheel and grinding wheel housings removed;

Figure 6 is an enlarged transverse section taken on the line 6—6 of Figure 1;

Figure 7 is a perspective view of one form of workpiece upon which the machine is adapted to operate; and

Figure 8 is an end view showing the condition of the workpiece prior to the grinding operation.

The machine selected for illustration is especially constructed to grind a radius on the forward edge of the type of bar employed in constructing bullet-proof grilles utilized in armored vehicles to protect radiators, etc.

As shown in Figure 7, the bar 10 is an elongated, relatively flat bar of somewhat tear-drop formation in section which is provided with a rounded forward edge 11 at its thickest section. This type of bar is normally made by a rolling operation in which two sections are rolled simultaneously, as indicated by the dotted and full lines in Figure 8, the thicker portions of the two sec-

tions being joined by a thin web section, indicated generally at 12. Thereafter, the strip is split down the middle at the web section 12 and to complete the bar it is necessary to remove the small projecting flange 13 in order to suitably round the forward edge of the bar. Since these bars are made of armor plate, they are exceedingly difficult to machine and, consequently, the machine of the present invention is provided to grind off the flanges or web projections and suitably round the forward edge. It will be appreciated, however, that the machine of the present invention may be adapted to form radius portions on any type of strip material.

Referring to Figures 1 to 6 of the drawings, the machine comprises a frame, which may be of any suitable construction, consisting primarily of four channel-shaped corner posts 15, 16, 17 and 18 connected intermediate their ends by side plates 20 and end plates 21. The upper ends of legs 15 and 18 are connected by a cross bar 22, while the upper ends of legs 16 and 17 are connected by a similar cross bar 23. The space above one of the side plates 20 is closed by a hinged panel consisting of a rectangular framework 24 hinged at 25 to the leg 15 and at 26 to an upright corner post 27 mounted on cross bar 22. The framework 24 is closed by a panel indicated fragmentarily at 28, the main portion of the panel being broken away in Figure 1 to show the interior of the machine. The hinged panel 24 is provided at its free edge with a pair of projecting lugs 30 spaced apart to receive the shank of an eyebolt 31, which is pivoted on a pin 32 carried by a pair of lugs 33 fastened to a corner post 34 mounted on the forward end of cross bar 23 and similar in construction to the corner post 27.

Also mounted at either side of the machine adjacent the rear thereof is a pair of identical side plates 35, one of which is shown in Figure 2. The top rear edges of the side plates 35 are connected by a cross bar 36, to which is fixed intermediate its ends a pair of uprights 37 connected by a plate 38.

A pin 39, fixed in the upper ends of the uprights 37, pivotally supports a housing 40 for a pair of grinding wheels 42. The housing 40 carries a forwardly extending coverplate 43 which rests upon the frame 24 at the front of the machine. All of the remaining exposed portions of the machine are preferably enclosed by suitable fixed sheet metal panels, which have been omitted from the drawings for the sake of clarity.

The grinding wheels 42 form part of an independent grinding or buffing machine of conven-

tional construction, being mounted upon a spindle 44 carried at the extremity of an arm 45 and being driven by a V-belt 46 engaging a pulley 47. The arm 45 is bifurcated and hence supports the grinding wheel spindle at each side of the housing 40. The arm, which carries a motor, not shown, for driving the belt, may be mounted in any conventional manner, as upon a vertical post upon which it may be adjustably positioned. Conventional means are included in the grinding machine for accurately adjusting the height of the extremity of arm 45, which carries the grinding wheels.

The grinding wheels are placed in the position shown in the drawings by lifting the pivoted cover 43 and moving the grinding wheel into position, whereupon the cover may be replaced.

The machine includes a work supporting carriage, shown best in Figures 3, 4, 5 and 6, of generally box-like construction, including a bottom wall 59, a pair of end walls 51 and 52, and a continuous side wall 53 provided with a pair of slots 54 in the neighborhood of the grinding wheels. The opposite side of the carriage is formed by five identically constructed, vertically extending plates 56, one located between the wheels and two located at the outer sides of the wheels.

The upper end of each of the plates 56 is notched at its corners to receive a pair of blocks 57. The blocks 57 for the adjacent corners of the two outer pairs of plates 56 are formed as one piece, bridging the space between the outer pairs of plates. All of the blocks 57 project inwardly to support the top members of the work supporting carriage. The central member 56 is provided with a top member 59 secured by cap screws 60 to the blocks 57 at one end and to the wall 53 at the other. The outer pair of plates 56, shown at the right-hand side of Figure 3, is connected by a common top member 61 to the side wall 53, the top member 61 being secured by cap screws 64 to the blocks 57 and to the wall 53. The plates 56 are also connected to the bottom wall 59 by means of cap screws 65. In consequence of this arrangement, the plates 56 and the top plates 59 and 61 may be readily removed.

The carriage is provided with five identically constructed backing rollers 70, one being located opposite each of the side plates 59. The backing rollers, as best shown in Figure 4, are provided with a cylindrical section 71, a flange 72 at the upper end of each roller, and a radius 73 connecting the flange 72 with the cylindrical portion 71. The radius 73 corresponds to the radius at the edge of the workpiece 10 and, consequently, the backing rollers 70 serve to locate the work strip in the manner best shown in Figure 4.

The backing rollers 70 are formed integrally with spindles 75 and 76 journaled in ball bearings 78 in the bottom wall 50 and in the plates 59 and 61. Spindle 75 carries a gear 79 secured thereto by means of a key 80. Each of the gears 79 meshes with a gear 81, which is formed integrally with a roller 82 journaled by means of ball bearings 83 on a spindle 84. The spindle 84 is pivotally mounted upon a pin 85 carried by a U-shaped bracket 86, which embraces the spindle 84 and is fixed to one of the plates 56 by means of a cap screw 87. The lower end of the spindle 84 is connected by means of a pin 88 to the bifurcated end of a bolt 89, which slidably projects through an opening in plate 56 and carries a spring 90, the tension of which may be adjusted by a pair of nuts 91.

As a result of this arrangement, it will be ap-

parent that the tension of spring 90 tends to swing the spindle 84 clockwise about the pin 85 and force the roller 82 against the work strip 10, thus holding it in proper relation with respect to the back-up roller 70.

The upper end of the spindle 84 is received within an elongated slot 92 formed in the top plate 61 or 59, as the case may be, it being understood that there is one roller 82 for each of the back-up rollers 70 and that all of the rollers 82 are mounted in the same manner. Each pair of gears 79 and 81 is housed by a housing 94, and oil seals 95 and 96 are mounted in the openings in the housing 94 and surround the hubs of the gears 79 and 81, respectively. The openings in plates 59 and 61 through which the upper ends of the spindle 76 project are closed by means of removable plates 98, while the openings 92 are closed by removable plates 99.

A sheet metal housing 102 is located adjacent each of the outer pairs of vertical plates 56 and contains the mounting mechanism for a pair of rollers 103 adapted to engage the bottom edge of the work strip in the manner best shown in Figure 4, the rollers 103 being provided with grooves 104 for receiving the bottom edge of the strip. Between the central plate 56 and each of the two outer pairs of plates is a pair of housings 105, each of which houses the mounting mechanism for a single roller 106 identical in construction and mode of operation to the rollers 103. There are thus provided five rollers like the rollers 103 engaging the bottom edge of the strip and, since all are identical and are identically mounted, only one need be described in detail.

As best shown in the broken away portion of Figure 3 and in Figures 4 and 5, the rollers 103 and 106 are journaled on shouldered bolts 107 carried at the extremities of levers 108, each of which is pivotally mounted on a pin 109 carried at the upper end of a standard 110 fixed to the lower wall 50 of the carriage. The opposite extremities of the levers 108 are pivoted by pins 111 to the heads of bolts 112, which slidably project through openings in the bottom wall 50. A spring 113 surrounds each bolt 112 and its tension may be adjusted by means of nuts 114 in order to adjust the force with which the rollers 103 are urged against the work strip. A stop 115, fitted in a suitable opening in the bottom wall 50, engages the lever 108 and limits movement of the lever in the direction in which it advances the roller toward the work.

A pair of circular discs 120 is fixed, respectively, to the end walls 51 and 52 of the carriage. Each disc is provided with a peripheral groove or roller track 121, which is engaged by seven circumferentially spaced rollers 122 that are journaled by means of ball bearings on trunnions 123, which project through suitable openings in the end plates 35 and are secured in position by means of nuts 125. As a result of this arrangement, the carriage as a whole may oscillate about an axis passing through the center of the discs 120. The discs are so arranged that this axis coincides with the axis of the radius on the work strip to be ground.

As best shown in Figure 6, end plate 52 has a projecting ear 127, which is connected by means of a pivoted link 128 to a crank arm 129 fixed on a short shaft 130, which is journaled in a bearing 131 secured to the upper edge of the end plate 51. The outer end of the shaft 130 carries a sprocket 132, which may be driven from

any suitable source of power by means of a sprocket chain, in the usual manner. It will be apparent that on rotation of the shaft 130 crank arm 129 and link 128 will effect an oscillatory movement of the work supporting carriage.

An elongated metal housing 135 is secured to the underside of the bottom wall 50 of the carriage and houses not only the lower ends of the bolts 112, but also a shaft 136 mounted at spaced points along its length in bearings 137 secured by means of cap screws 138 to a downwardly projecting portion of the side wall 53. The bearings 137 support the shaft 136 in the plane of the axes of the back-up rollers 170. The lower spindle 75 on each back-up roller carries a bevel gear 140 which meshes with a bevel gear 141 mounted on the shaft 136, there being one bevel gear 141 for each of the back-up rollers.

As best shown in Figure 3, the right-hand extremity of the shaft 136 carries a ratchet wheel 143 and a double armed link 144, one arm of which lies on each side of the ratchet wheel 143 and is journaled on the shaft 136. A pawl 145 is pivotally carried on a pin 146 mounted on the lever 144 between the arms of the lever 144; and a leaf spring 147, fixed to the lever by means of screws, normally urges the pawl into engagement with the ratchet wheel. The lower end of the lever 144 carries a pin 148 on which is journaled a roller 149.

As best shown in Figure 2, when the carriage is oscillated in a counterclockwise direction to its extreme position, the shaft 136 swings from its lower position, in which it supports the lever 144 in the position shown in solid lines, to the position indicated in dotted lines by the numeral 136'. During this movement the roller 149 on the end of the lever 144 hits a ratchet operating member 150, thereby swinging the arm 144 clockwise about the shaft 136' and, consequently, rotating the ratchet wheel and the shaft 136', through a small portion of one revolution. This rotation of the shaft 136 is transmitted through gears 140 and 141 to the back-up rollers 70 and by the gears 79 and 81 to the rollers 82, thereby rotating all of the rollers 70 and 82 in a direction to feed the strip lengthwise by an amount slightly less than the width of the grinding wheels 42.

It will be observed that this work feeding movement occurs when the carriage is at one of its extreme positions of oscillation and that, moreover, it occurs during the time in which the grinding wheels 42 are out of contact with that portion of the work strip indicated by the bracket 152 in Figure 4 which requires grinding.

The ratchet operating member 150 is pivoted on a pin 154 fixed in an arm 155 carried at the upper end of a lever 156, which is pivoted by means of a shouldered cap screw 157 to a block 158 fixed to the corner post 17. An elongated opening 159 formed in the member 150 receives a pin 160 carried by the member 155 and thus limits the oscillation of the member 150 about its pivot pin 154. A spring 161 is mounted between the lower end of the member 150 and the member 156 and normally tends to separate the two, thereby forcing the upper end of the member 150 to the left, as viewed in Figure 2. The pivotal mounting of the member 150, together with the spring 161, cushions the shock incident to contact between the member 150 and the roller 149.

In order to adjust the feed of the work, the position of the member 150 may be shifted by swinging vertical arm 156 about its pivot 157.

This is accomplished by means of a threaded bar 162, which passes through suitable openings in the side wall member 20, and a bracket 163 mounted on the side wall. A pair of nuts 164 threaded on the member 162 at opposite sides of the bracket 163 may be rotated to adjust the position of the threaded bar 162 and lock it in adjusted position. The inner end of the threaded bar 162 carries a member 165 provided with a slot 166, which receives a pin 167 carried by the member 155. Consequently, adjustment of the position of the threaded bar 162 adjusts the position of the member 155 and arm 156 about the pivot 157 and thus controls the distance which the work is fed on each oscillation.

As best shown in Figure 2, the side plates 35 are provided with circular openings of approximately the diameter of the discs 120, so that the ends of the carriage are exposed at either end of the machine. The discs 120 are also provided with openings through which the work strip may be inserted, and a trough formed of three plate members 170, 171 and 172 is fixed by means of a plate 173 to each disc 120 in order to guide the work strips entering and leaving the machine. A pair of horizontal plates 174 is secured to the trough member at either side thereof to give it transverse rigidity.

The operation of the machine will be obvious from the previous description. It is only necessary to position the grinding wheels accurately with respect to the carriage and start one of the strips by hand by placing it in the trough at the entering side of the machine and forwarding it into a position where it will be engaged by the rollers 70 and 82. From then on the machine automatically oscillates the work back and forth about the axis of the carriage and feeds the work step by step past the grinding wheels. The work feeding movement occurs during an idle portion of the oscillating stroke of the carriage and, consequently, will not interfere with the grinding operation.

Any desired number of wheels may be employed. It will be observed, however, that in the machine illustrated, employing two wheels, each portion of the surface to be ground is subject to four grinding operations due to the fact that the work is oscillated in one direction and then returned in contact with the wheel between each work feeding step and the fact that the two wheels are operating simultaneously. The angle of oscillation may be readily adjusted to accommodate a radius of any desired arc by varying the length of the crank arm 129, and the radius may be adjusted by varying the height of the wheels. Likewise, the amount of work feed may be adjusted by adjusting the position of threaded rod 162.

While only one specific embodiment of the invention has been shown and described, it will be apparent that various changes and modifications may be made without departing from the spirit of the invention, the scope of which is commensurate with the appended claims.

It will be understood that while the particular machine illustrated is adapted for use in connection with an independent grinding machine of conventional construction, the machine may incorporate its own grinding wheel spindle support and be a self-contained complete machine without departing from the spirit of the invention.

What is claimed is:

1. A mechanism for supporting and feeding strip material to a grinding wheel for grinding a radius

on the strip material comprising a stationary frame, a work supporting carriage pivotally mounted on the frame and adapted to support strip material with the axis of the radius to be ground on the material coinciding with the axis of pivotal mounting of the carriage, means to oscillate the carriage, and means on the carriage for feeding the work endwise.

2. A mechanism for supporting and feeding strip material to a grinding wheel for grinding a radius on the strip material comprising a stationary frame, a work supporting carriage pivotally mounted on the frame and adapted to support strip material with the axis of the radius to be ground on the material coinciding with the axis of pivotal mounting of the carriage, means to oscillate the carriage, and means on the carriage for feeding the work endwise step by step upon the completion of each cycle of oscillation of said carriage.

3. A mechanism for supporting and feeding strip material to a grinding wheel for grinding a radius on the strip material comprising a stationary frame, a work supporting carriage pivotally mounted on the frame and adapted to support strip material with the axis of the radius to be ground on the material coinciding with the axis of pivotal mounting of the carriage, means to oscillate the carriage about an arc in excess of the arc of the radius to be ground, and means to feed the work endwise step by step upon the completion of each cycle of oscillation of said carriage when the grinding wheel is out of contact with the surface of the work requiring grinding.

4. A mechanism for supporting and feeding strip material to a grinding wheel for grinding a radius on the strip material comprising a frame, a work supporting carriage pivotally mounted on the frame on an axis parallel to the grinding wheel axis, a plurality of rollers journaled on said carriage and adapted to engage and locate a work

strip for movement in a direction parallel to the grinding wheel axis with the center of the radius to be ground on the workpiece located on the axis of the pivotal mounting of the carriage, means to oscillate the carriage, and means to rotate said rollers and thus feed the work past the grinding wheel.

5. A mechanism for supporting and feeding strip material to a grinding wheel for grinding a radius on the strip material comprising a frame, a work supporting carriage pivotally mounted on the frame on an axis parallel to the grinding wheel axis, a plurality of rollers journaled on said carriage and adapted to engage and locate a work strip for movement in a direction parallel to the grinding wheel axis with the center of the radius to be ground on the workpiece located on the axis of the pivotal mounting of the carriage, means to oscillate the carriage, and means to rotate said rollers and thus feed the work past the grinding wheel step by step upon the completion of each cycle of oscillation of said carriage.

6. A mechanism for supporting and feeding strip material to a grinding wheel for grinding a radius on the strip material comprising a frame, a work supporting carriage pivotally mounted on the frame on an axis parallel to the grinding wheel axis, a plurality of rollers journaled on said carriage and adapted to engage and locate a work strip for movement in a direction parallel to the grinding wheel axis with the center of the radius to be ground on the workpiece located on the axis of the pivotal mounting of the carriage, means to oscillate the carriage about an arc in excess of the arc of the radius to be ground, and means to rotate said rollers and thus feed the work past the grinding wheel step by step upon the completion of each cycle of oscillation of said carriage when the grinding wheel is out of contact with the surface of the work requiring grinding.

PAUL E. CARRICK.
